PRESSURE REDUCING VALVE

James J. Lawler, Mount Vernon, N. Y., assignor
to Lawler Automatic Controls, Inc., Mount
Vernon, N. Y., a corporation of New York

Application October 29, 1931, Serial No. 571,887

3 Claims. (Cl. 236—42)

This invention relates to certain new and useful improvements in pressure reducing valves.

The primary object of the invention is to provide a pressure reducing valve preferably adapted 5 for association with a steam heating system of the one or two pipe character for regulating the pressure of steam delivered to a radiator or other element, the reducing valve embodying a thermostatic element with which the steam flows in 10 contact for regulating the flow of steam and thereby controlling the pressure within a radiator or like device beyond the reducing valve.

With the above and other objects in view that will become apparent as the nature of the invention is better understood, the same consists 15 in the novel form, combination and arrangement of parts hereinafter more fully described, shown in the accompanying drawing and claimed.

In the drawing:—

20 Figure 1 is a side elevational view of a two pipe steam radiator wherein the radiator is equipped with steam supply and return pipes with the pressure reducing valve set into the steam supply pipe;

25 Figure 2 is a vertical cross-sectional view of the pressure reducing valve showing the thermostatic element therein for moving the valve toward its seat to regulate the amount of flow of steam therethrough whereby the pressure beyond 30 the valve may be regulated;

Figure 3 is a bottom plan view of the valve casting cap; and

35 Figure 4 is a fragmentary side elevational view, partly in section, showing the pressure reducing valve embodied in a one pipe steam heating system.

Referring more in detail to the accompanying drawing and particularly to Figures 1 to 3, the reference numeral 10 designates a steam radiator having a steam supply pipe 11 communicating 40 with one end thereof and a steam return pipe 12 attached to the other end of the radiator. The pressure reducing valve designated in general by the reference numeral 13 is set into the 45 steam supply pipe 11 adjacent its point of connection with the radiator and said steam supply pipe 11, outwardly of the pressure reducing valve may include a shut-off for automatic temperature control valve 14, the valve 13 being provided 50 alone for the purpose of reducing steam pressure within the radiator.

The pressure reducing valve comprises a bowl shaped casing 15 having an internally threaded connector 16 at its lower end for attachment 55 to the steam supply pipe 11 while the upper end

of the casing 15 is externally threaded for the head or cap member that comprises a horizontal wall 17 carrying an internally threaded depending annular flange 18 for threaded engagement with the upper end of the casing 15, the cap being 60 provided with a central opening surrounded by an upstanding exteriorly threaded collar 19 for attachment to the temperature control valve 14, or by means of an elbow with the radiator. An annular valve seat 20 is disposed within the casing 15 at the upper end of the connector 16 and is surrounded by an annular channel 21 for purposes presently to appear.

The pressure reducing valve further includes a thermostatic member comprising inner and outer 70 concentric walls 22 and 23 defining an annular channel 24, the channel being closed at its lower end by a flanged cap 25 while the upper end of the channel is closed by a flanged head 26. The flanged head 26 carries an upstanding plug 27 75 overlying the center channel within the inner annular member 22 and said plug has a threaded socket therein with a bottom wall having an opening 28 closed by a gasket 29 that is engaged by a screw plug 30. An expansible tube is located 80 within the center channel, the corrugated tube 31 having its closed lower end 32 normally projecting below the bottom cap 25 while the open upper end 33 of the tube is threaded into engagement with the inner face of the inner annular member 85 22 as at 33 with the open upper end of the expansible tube disposed below the openings 34 in the inner annular member. The thermostatic device is charged with expansible fluid through the apertured plug 27, the fluid first filling the 90 expansible tube and then overflowing through the openings 34 into the annular channels 24. The thermostatic element is retained at its limit of upward movement within the pressure reducing valve casing 15 by the coil spring 35 that is seated 95 at one end in the annular channel 21 of the valve casing with the other end thereof engaged with the lower end of the thermostatic element and as shown in Figure 3, the inner face of the wall 17 of the cap member of the valve casing is provided with radial ribs that is engaged by the upper end of the thermostatic member element so that a circulation of steam through the reducing valve 100 is permitted at all times.

The valve within the casing 15 comprises the valve body 37 having a socket 38 in its upper end to receive the lower projecting end 32 of the expansible tube 31, the valve member 37 being disposed within the coil spring 35 and carrying upon 110

its lower end a renewable valve face 39 retained in position by the screw pin 40.

Steam flows through the casing of the pressure reducing valve in the direction of the arrows shown in Figure 2, the steam passing over the valve seat 20, around the thermostatic element and between the head of the thermostatic element and the wall 17 of the casing cap to outlet through the collar 19 around the plug 27 for delivery to the radiator 10, heat from the machine causing the expansible fluid to expand which imparts expansive movement to the tube 31 for lowering the valve body 37 toward the seat 20 against the pressure of steam flowing through the valve casing 15, the degree of pressure of steam to be delivered to the radiator being controlled by the amount of expansive fluid placed in the thermostatic element, the valve member 37 never closing upon its seat 20, but approaching the same in response to action of the expansible tube 31 for regulating the pressure of steam flowing through the valve casing. The pressure of steam supply from a source of energy is always in excess of that required for heating purposes or the like and the installation of the pressure reducing valve reduces the pressure of steam supply to the point required, but this pressure reducing valve in no manner completely obstructs the flow of heating medium, its sole purpose being to reduce the pressure of steam through the point required.

In the application of the invention as illustrated in Figure 4, the same is embodied in a one pipe steam heating system, the pipe 41 from a source of steam supply having an elbow fitting 42 therein carrying an outlet pipe 43 for high pressure steam service, the pipe 41 outwardly of the elbow 42 having a pressure reducing valve 13a in communication therewith, the cap 17a for the valve casing 15a being closed at its upper end and said valve casing 15a has a side outlet 19a connected to a steam service pipe 44. The thermostatic element 23a is spring supported as at 35a with its valve body 37a spaced from the valve seat 20a. With this system, steam at high pressure may be utilized for certain purposes and the pressure reducing valve is employed for reducing the pressure of steam delivered to radiators or other elements where desired.

From the above detailed description of the invention, it is believed that the construction and operation thereof will at once be apparent and

while there are herein shown and described the preferred embodiments of the invention, it is nevertheless to be understood that minor changes may be made therein without departing from the spirit and scope of the invention as claimed.

I claim:

1. A pressure reducing valve comprising a casing having a valve seat at its inlet end, a floating valve in the casing adjacent the seat and a thermostatic element engageable with the valve for moving the same towards its seat against fluid pressure through the casing, means for holding the thermostatic element engaged with the end of the casing opposite the valve seat, said thermostatic element comprising a pair of spaced concentric walls defining an annular chamber and a central passage, an expansible tube in the central passage engaged with the inner wall and having its closed lower end engaged with the valve and the open upper end in communication with the annular chamber at a point below the upper end of the annular chamber.

2. A pressure reducing valve comprising a casing having a valve seat at its inlet end, a floating valve in the casing adjacent the seat and a thermostatic element engageable with the valve for moving the same towards its seat against fluid pressure through the casing, means for holding the thermostatic element engaged with the end of the casing opposite the valve seat, said thermostatic element comprising a pair of spaced concentric walls defining an annular chamber and a central passage, an expansible tube in the central passage engaged with the inner wall and having its closed lower end engaged with the valve and the open upper end in communication with the annular chamber at a point below the upper end of the annular chamber.

3. A pressure reducing valve comprising a casing having opposite inlet and outlet openings and a pressure reducing valve including a floating thermostatic element movable axially of the inlet and outlet openings, the thermostatic element including an outer annular stationary part and a central movable part with the movable part engaged with the valve, and a spring for holding the stationary part against movement.
